By Oakwell Chubbings

UNITED STATES PATENT OFFICE.

HARRY C. ADAM, OF ST. LOUIS, MISSOURI.

LIGHTING-FIXTURE.

1,189,520.

Specification of Letters Patent.

Patented July 4, 1916.

Application filed September 18, 1915. Serial No. 50,496.

To all whom it may concern:

Be it known that I, HARRY C. ADAM, a citizen of the United States, residing at St. Louis, Missouri, have invented a certain new and useful Improvement in Lighting-Fixtures, of which the following is a full, clear, and exact description, such as will enable others skilled in the art to which it appertains to make and use the same.

10 This invention relates to indirect and semi-indirect lighting fixtures of the type in which a diffusing shield or bowl is arranged under the lighting unit some distance from the underside of the top reflector of the fixture. In the fixtures of this general type that are now in use the diffusing shield or bowl is suspended from the top reflector by means of chains or links and the top reflector is connected to the ceiling or to a supporting structure in various ways.

15 The main object of my present invention is to provide an inexpensive lighting fixture of the general type mentioned that presents a neat and ornamental appearance and to 20 this end I have devised a fixture in which both the top reflector and the diffusing shield or bowl are carried by a plurality of rods, bars or pieces of heavy wire that are connected to a supporting element, preferably a shell that is arranged above the top reflector and which forms a housing for the electric lamp socket that supports the lighting unit, said shell being arranged adjacent the ceiling of the room or mounted on a pipe, chain 25 or piece of tubing that depends from the ceiling.

Another object is to provide an inexpensive lighting fixture of the general type mentioned, which is so constructed that the top reflector and the diffusing shield or bowl can be adjusted easily to adapt the fixture to electric lamp bulbs of different sizes without destroying the proper relation between the filament of the bulb and the top reflector and 30 bowl.

Other objects and desirable features of my invention will be hereinafter pointed out.

Figure 1 of the drawings is a side elevational view, partly in vertical section, of a 35 lighting fixture constructed in accordance with my invention. Fig. 2 is a similar view of a fixture constructed in accordance with my invention, which is adapted to be mounted on a pipe or tube that depends from the ceiling of a room. Fig. 3 is a bottom plan view of the shell that incases the lamp socket

and which acts as a support for the devices that carry the top reflector and the diffusing shield or bowl; and Fig. 4 is a detail sectional view, illustrating a slight modification of my invention.

Referring to the drawings, which illustrate the preferred form of my invention, A designates the top reflector of the fixture, which may be formed either of metal or of translucent material, the underside of said top reflector being enameled or coated with a brilliant reflecting surface if said member is formed of metal.

B designates the diffusing shield or bowl that is arranged under the lighting unit C, which preferably consists of a single electric lamp bulb, said bowl B being formed either of translucent material or of opaque material, depending upon whether the fixture is a semi-indirect or an indirect fixture. The lamp bulb C is carried by a lamp socket D and said lamp socket is incased by a shell E that projects upwardly above the top reflector A. The lamp socket D may either be connected to a supporting device 1 on the ceiling of a room and the shell E also connected to said supporting device, as shown in Fig. 1, or said lamp socket and shell can be mounted on a pipe, chain or tubular shaped supporting device 1^a that depends from the ceiling, as shown in Fig. 2.

The top reflector A and the bowl B are both carried by a plurality of devices 2 which are supported by the shell E, which devices 2 project downwardly through a center opening in the top reflector. In the preferred form of my invention, as herein shown, the devices 2 consist of short pieces of heavy wire or light-weight rods which are provided at their upper and lower ends with hooks 2^a and 2^b that engage the shell E and the bowl B, respectively, said devices 2 being provided intermediate their ends with portions 2^c on which the top reflector A rests, as shown clearly in Fig. 1. The reflector supporting portions 2^c of the devices 2 may be formed in various ways without departing from the spirit of my invention, but I prefer to provide each of said devices with a coil so that the device will have a certain degree of resiliency, the coil constituting the reflector supporting portion 2^c of the device. The devices 2 are preferably so designed that the lower edge 100 of the shell E will be arranged a short distance above the edge of the center opening

in the top reflector A, and in the preferred form of my invention, as herein shown, the shell E is provided with openings 3 for receiving the hooks 2^a at the upper ends of the devices 2. The shell E is preferably provided with means for holding the devices 2 in a vertical position, which means may consist of an outwardly projecting flange 4 at the lower end of the shell E, which is provided with notches 5 that receive the devices 2, as shown in Fig. 1. I prefer to arrange the devices 2 on the exterior of the shell E, as shown in Fig. 1, but if desired, said devices may be arranged on the interior of said shell. When the devices 2 are arranged on the interior of the shell, as shown in Fig. 4, the shell is provided at its lower end with an inwardly-projecting, notched flange for holding said devices in a vertical position. The bowl B is provided at its upper edge with an outwardly-projecting portion or flange 6 that cooperates with the hook 2^b on the device 2, and when said bowl is in engagement with said devices, as shown in Fig. 1, it holds said devices pressed tightly against the edge of the center opening in the top reflector A, thus securely holding said reflector in position and preventing the devices 2 from becoming disengaged from the shell E that supports said devices.

In order that different sized lighting units may be used without destroying the proper relation between the filament of the lighting unit and the reflector A and bowl B, I have provided the shell E with a plurality of sets of openings arranged in different horizontal planes for receiving the hooks 2^a on the devices 2, thereby enabling the top reflector and the bowl or diffusing shield to be raised and lowered with relation to the lamp socket D that supports the lighting unit. In the form of my invention herein shown the shell E is provided with a set of top openings 3 and a set of bottom openings 3^a that are arranged in a lower horizontal plane. When a short bulb C is used, the hooks at the upper ends of the devices 2 are inserted in the top openings 3, and when a longer bulb is used, said hooks are inserted in the set of bottom openings 3^a. The flange 4 at the lower end of the shell E is provided with a separate set of notches 5^a for receiving the sustaining devices 2 when the hooks 2^a at the upper ends of said devices are arranged in the lower set of openings 3^a of the shell, the notches 5^a being a trifle deeper than the notches 5 so that the devices 2 will extend approximately parallel to the sleeve E when said devices are arranged in their lowermost position.

The particular cross-sectional shape of the top reflector A is immaterial, so far as my present invention is concerned, but I prefer to provide said reflector with two

oppositely-inclined reflecting surfaces α and β that incline upwardly from the outer edge of the reflector and from the inner edge of the center opening of the reflector, respectively. It is also immaterial how the sustaining devices 2 are connected to the supporting element E, and while I have shown said supporting element provided with slots or opening for receiving hooks on said sustaining devices, I wish it to be understood that said devices could be connected to the supporting element E in various other ways without departing from the spirit of my invention. Furthermore, it is not essential that the devices 2 be sprung over the upper edge portion of the shield B, as various other means could be employed for securing said devices and shield together. In all forms of my invention, however, the devices 2 will be in the nature of rods, bars, strips or members of any preferred cross-sectional shape, size or material that have sufficient rigidity to hold the reflector and shield in proper position.

A lighting fixture of the construction above described can be manufactured cheaply, as it comprises only a few parts of simple design; it can be installed and removed easily and it can be modified easily to adapt it to different sized lighting units, owing to the fact that the top reflector and diffusing shield or bowl are always held in fixed relation with each other by a supporting structure that can be raised and lowered with relation to the lamp socket that carries the electric lamp bulb which constitutes the lighting unit of the fixture.

Having thus described my invention, what I claim, and desire to secure by Letters Patent, is:

1. A lighting fixture comprising a top reflector, a shield arranged under the source of light, and a plurality of sustaining devices for said shield consisting of rods provided with bent portions on which said top reflector rests.

2. A lighting fixture, comprising a top reflector, a shield arranged under the source of light, and a plurality of sustaining devices that support said reflector and shield, each of said devices consisting of a single member or element having a relatively long shank provided intermediate its ends with means that assists in carrying the weight of said top reflector, and provided at its opposite ends with means that cooperates with a supporting structure and with said shield.

3. A lighting fixture, comprising a top reflector, a shield arranged under the source of light, and a plurality of sustaining devices that carry said top reflector and shield and which are held pressed tightly against the shield by reason of said top reflector bearing upon said devices.

4. An electric lighting fixture compris-

ing a shell that forms a housing for the lamp socket in which the lighting unit is mounted, a top reflector, a shield arranged under the lighting unit, and rods detachably connected to said shell and acting as a support for the shield and the top reflector.

5. A lighting fixture comprising a top reflector, a shield arranged under the source of light, a supporting element arranged above the top reflector, a plurality of sustaining rods for said shield that depend from said supporting element, and integral portions on said rods that carry said top reflector and said shield.

15 6. A lighting fixture, comprising a top reflector, a shield arranged under the source of light, a supporting element arranged above said top reflector and consisting of a housing for the means that carries the lighting unit of the fixture, depending sustaining devices on said supporting element that project downwardly through a center opening in the top reflector and which are connected at their lower ends to said shield, and means on said devices arranged intermediate the ends of same for sustaining the weight of said top reflector.

7. In a lighting fixture, a supporting element, depending devices loosely hooked onto said element in such a manner that they can be easily disconnected therefrom without the necessity of removing separate fastening devices, means on said supporting element that prevent said devices from swinging, a shield arranged under the source of light and carried by said depending devices and a top reflector having a center opening through which said devices pass.

40 8. A lighting fixture comprising a shield arranged under the source of light, a supporting element, substantially rigid sustaining devices for said shield, each of which consists of a single piece of metal that is detachably connected to said supporting element, and a top reflector supported in operative position by said sustaining devices.

9. A lighting fixture comprising a top reflector, a shield arranged under the source of light, a shell arranged above the top reflector, a plurality of sustaining devices for said shield detachably connected to said shell and projecting downwardly through a center opening in the top reflector, and portions on said devices on which the top reflector rests freely.

10. A lighting fixture comprising a top reflector, a shield arranged under the source of light, a shell arranged above the top reflector and acting as a housing for the means that carries the lighting unit of the fixture, said shell having openings, and sustaining devices for said shield and top reflector having portions that enter the openings in said shell.

11. A lighting fixture comprising a top reflector, a shield arranged under the source of light, a shell arranged above the top reflector and acting as a housing for the means that carries the lighting unit of the fixture, 70 said shell having openings, and sustaining devices for said shield and top reflector connected to said shell and each consisting of a piece of wire or rod provided at its upper and lower ends with hooks that engage the 75 shell and shield, respectively, and provided intermediate its ends with a portion on which said top reflector rests.

12. A lighting fixture comprising a top reflector, a shield arranged under the lighting unit, a shell arranged above the top reflector and acting as a housing for an electric lamp socket that carries the lighting unit, sustaining rods for said shield and top reflector that are loosely connected to said 85 shell in such a manner that they can be easily disconnected therefrom, and means on said shell for holding said sustaining rods in proper position with respect to said shell.

13. A lighting fixture comprising a shell 90 that forms a housing for an electric lamp socket, a top reflector having a center opening, a shield arranged under the lighting unit of the fixture, sustaining devices for said shield and top reflector detachably connected to said shell, and a notched flange on said shell that holds said sustaining devices in proper position.

14. A lighting fixture comprising a top reflector, a shield arranged under the lighting unit of the fixture, a supporting element arranged above the top reflector and acting as a housing for a lamp socket which carries the lighting unit, and a vertically adjustable means on said supporting element 105 that carries said top reflector and shield.

15. A lighting fixture comprising a top reflector, a shield arranged under the lighting unit of the fixture, a supporting element arranged above the top reflector and acting 110 as a housing for a lamp socket which carries the lighting unit, and means detachably connected to said supporting element for carrying said top reflector and shield, said means being adapted to be raised and lowered with relation to the supporting element 115 so as to adapt the fixture to different sized lighting units.

16. A lighting fixture comprising a supporting element, a top reflector, a shield arranged under the source of light, sustaining devices detachably connected to said supporting element for carrying said top reflector and shield, and means on said supporting element for permitting said sustaining devices to be connected to same at a higher or a lower point so as to adapt the fixture to different sized lighting units.

17. An electric lighting fixture comprising a top reflector, a shell arranged above said 130

reflector and acting as a housing for an electric lamp socket, devices detachably connected to said shell and projecting downwardly through a center opening in said top reflector, and a shield supported by said devices and acting to hold said devices pressed tightly against the edge of the center opening in the top reflector.

In testimony whereof I hereunto affix my signature in the presence of two witnesses, 10 this tenth day of September 1915.
